UNITED STATES PATENT OFFICE.

DONALD F. WHITING, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed July 22, 1919. Serial No. 312,641.

To all whom it may concern:

Be it known that I, DONALD F. WHITING, a citizen of the United States, residing in New York, in the county of Bronx and State of New York, have invented certain new and useful Improvements in Telephone Systems, of which the following is a full, clear, concise, and exact description.

This invention relates to telephone systems and more particularly to a system provided with attenuation equalizing means for the voice frequency range so that it will transmit voice currents without serious distortion and at the same time will transmit ringing currents or other signaling currents without having their strength reduced by the action of the attenuation equalizer.

The transmission through a telephone line generally varies in efficiency with the different frequencies. A line usually transmits the lower voice frequencies more efficiently than the higher voice frequencies. This is true even when the line is provided with loading coils and repeaters with associated transformers. It has been proposed heretofore to place in shunt to such a line at a suitable point an impedance or network of impedances which will discriminate against the lower voice frequencies by acting as a short circuit therefor to the desired extent. An equalizer of this type which is designed so that it will secure a total transmission of voice currents substantially without distortion is fully described in the patent to Ray S. Hoyt, No. 1,453,980, granted May 1, 1923. An attenuation equalizer may be defined as a device adapted to be connected to a line and having an attenuation which is complementary to the attenuation caused by the line over a range of frequencies.

Ringing or other signaling currents are however, of such low frequency that they are very inefficiently transmitted by the repeaters and associated transformers. When, therefore, they are sent over a line having a shunt equalizer of the above type, they would be materially reduced in amplitude if the equalizer were permitted to function in its normal manner. It is the object of this invention to provide means for effectively preventing the shunt equalizer from carrying currents of a particu-

lar frequency, such as that of the ringing currents.

This is accomplished in the embodiment of the invention herein disclosed by placing in the shunt path which contains the attenuation equalizer, a tuned circuit which is resonant to the frequency of the signaling current, thus rendering the shunt path anti-resonant to this frequency and effectively opening the shunt by offering a high impedance whenever signaling currents are being sent out on the line.

The invention will be more fully understood from the following detailed description and claims taken in connection with the accompanying drawings in which Fig. 1 is a portion of a circuit showing the invention placed directly between line wires, and Fig. 2 is a similar view showing the invention applied to a vacuum tube repeater.

Referring to the drawings by reference numerals, the line wires 10 and 11 form part of a line, the unequal attenuating effect of which it is desired to equalize. The equalizer 12 is shown in the drawings as having parallel inductance and capacity, indicated at 13 and 14, respectively. This, however, is for the purpose of illustration only, and it is to be understood that the equalizer will consist of such an arrangement of inductance, capacity, or resistance or combinations thereof as may be required by the transmission characteristics of the particular line with which it is to be used. In general, the impedance of the equalizer will be high for the higher frequencies in the voice range and relatively low for the lower frequencies.

In series with the equalizer 12 is a network 15 comprising parallel inductance and capacity 16 and 17 respectively. These form a circuit which is tuned according to the formula:

$$f = \frac{1}{2\pi\sqrt{LC}}$$

to the frequency of the signaling current employed on the line. This renders the shunt path containing the attenuation equalizer anti-resonant to the signaling currents, and since the tuned circuit 15 contains very little resistance it operates substantially to open the shunt path by offering a very high impedance whenever signaling

current is being used. In the above, the resistance of the tuned circuit has been assumed to be negligible. If, however, the resistance is considerable or if resistance is added in order to make the impedance to signaling currents substantially less than infinity, the formula for tuning is as follows:

$$10 \quad f = \frac{1}{2\pi} \sqrt{\frac{1}{LC} - \frac{R^2}{4L^2}}$$

Some resistance may be desirable in the tuned circuit, when it is desired to render its impedance high to a band of frequencies rather than to a single frequency. Such resistance may be incorporated in the inductance coil 16 or may be separate therefrom.

20 In Fig. 2 the line comprising wires 10 and 11 is inductively coupled to a vacuum tube repeater 18. The transformer 19 with midpoint connection 20 is employed for convenience in phantoming the line. Across 25 the primary of the input transformer 21 is connected the potentiometer 22 for controlling the amplification of repeater 18. The attenuation equalizer 12 and tuned circuit 15 are placed in series with potentiometer 30 22, where they function just as described above in connection with Fig. 1.

While two embodiments of the invention have been illustrated and described, it is to be understood that the invention is not limited to the forms shown but includes equivalent means for accomplishing its object within the scope of the appended claims.

What is claimed is:

1. In combination, a telephone circuit, 40 and a shunt path, the impedance of a portion of which is relatively high for one range of frequencies to be transmitted and relatively low for another range of frequencies to be transmitted, the impedance of another portion of said shunt path for a particular group of frequencies within said second mentioned range being very high as compared with its impedance for other frequencies to be transmitted, said two portions 50 being in series with each other.

2. In combination, a telephone circuit, and a shunt path, the impedance of a portion of which is relatively high for one range of frequencies to be transmitted and 55 relatively low for another range of frequencies to be transmitted, the impedance of another portion of said shunt path for a particular frequency within said second mentioned range being very high as compared with its impedance for other frequencies to be transmitted, said two portions 60 being in series with each other.

3. In combination, a telephone circuit, an

attenuation equalizer in shunt to said circuit, and a tuned circuit interposed between 65 said equalizer and one side of said circuit to render the shunt anti-resonant to a particular frequency.

4. In combination, a telephone circuit, an attenuation equalizer in a path in shunt to 70 said circuit and a network comprising parallel inductance and capacity in said path in series with said equalizer, said network being tuned to the frequency of signaling currents sent out on said circuit. 75

5. In combination, a telephone circuit, the attenuation of which is greater for high frequencies than for low frequencies, an equalizer network in shunt to said circuit and adapted to short-circuit low frequencies to 80 a greater extent than high frequencies, and means to render said shunt anti-resonant to a particular low frequency. 85

6. In combination, a line, a repeater, a transformer coupling said line to the input 85 of said repeater, and a potentiometer shunt connected across one winding of said transformer, said shunt comprising a variable resistance, a network adapted to equalize the transmission of voice currents, and a 90 tuned circuit to render said shunt anti-resonant to a signaling current frequency.

7. In combination, a line, a repeater, a transformer between said line and the input 95 of said repeater, and a potentiometer shunt connected across the primary of said transformer, said shunt comprising a variable resistance, a network adapted to equalize the transmission of voice currents, and a 100 tuned circuit to render said shunt anti-resonant to a signaling current frequency. 100

8. In combination, a repeater for alternating currents, a potentiometer effectively in shunt to said repeater, and an anti-resonant circuit in the shunt path comprising said potentiometer, said circuit being tuned to a frequency which is to be transmitted by said repeater with maximum efficiency. 105

9. In combination, a line, a voltage operated device connected thereto, a path containing resistance bridged across said line, and an anti-resonant circuit in said path to impede the passage of a frequency which is to be transmitted by said repeater with maximum efficiency. 110

10. In combination, a telephone line, a repeater, a transformer between said line and said repeater, a path comprising resistance in shunt to the primary of said transformer, and an anti-resonant circuit in said path 115 tuned to the signaling frequency employed on said line. 120

In witness whereof, I hereunto subscribe my name this 18th day of July A. D., 1919.

DONALD F. WHITING.
